UNITED STATES PATENT OFFICE.

LESTER KYLE ALDRICH, OF SIDNEY, OHIO.

PAPER-FOLDING MACHINE.

Application filed April 12, 1926. Serial No. 101,395.

The invention relates to paper folding machines and more especially to mechanism for making a loop fold.

The object of the present invention is to improve the construction of mechanism for making the loop fold and to provide a simple, practical and efficient construction which will be strong and durable and comparatively inexpensive and which will enable the folding plates to be adjusted to different angles according to how hard the stock is to bend and to permit the folding plates to be adjusted to various angles between ten degrees and forty-five degrees and to effect 10 the simultaneous adjustment of the nose of the upper folding plate so that the latter will in the various adjustments of the folding mechanism be arranged in proper position with relation to the paper level.

20 A further object of the invention is to provide a folding mechanism which will be particularly valuable in folding the lighter stocks which often fold prematurely while going up the incline due to the friction 25 caused by the plate diverting the sheet from its natural course, which is a straight line, and to enable the paper to travel in a nearer straight line than has heretofore been possible to avoid such premature folding of the 30 paper.

Another object of the invention is to provide adjustable folding mechanism in which the folding of the sheets will improve as the angle of the inclination of the folding plates is decreased and to enable paper of the lighter stocks and super-coated slick stock 35 to be successfully folded without liability of spoiling the sheets.

With these and other objects in view, the invention consists in the novel construction and combination and arrangement of parts hereinafter fully described, illustrated in the accompanying drawings and pointed out in the claims hereto appended, it being understood 40 that various changes in the form, proportion and minor details of construction, within the scope of the claims, may be resorted to without departing from the spirit or sacrificing any of the advantages of the 45 invention.

In the drawings:—

Figure 1 is a side elevation of a portion of a paper folding machine illustrating a folding mechanism having adjustable folding plates constructed in accordance with 55 this invention.

Fig. 2 is a plan view of the same.

Fig. 3 is a side elevation of a portion of the folding machine illustrating another method of adjusting the folding plates.

Figs. 4, 5, 6, 7, 8 and 9 are diagrammatic views illustrating the operation of the curved nose of the upper folding plate in making the loop fold.

Fig. 10 is a detail sectional view illustrating the construction for securing the folding plates in their adjustment.

Referring particularly to Figs. 1 and 2 of the drawings 1 designates the upper folding plate arranged at an inclination and adapted to be adjusted to various angles between forty-five degrees and approximately ten degrees and provided at its lower end with a curved nose 2 presenting a smooth convex cam face to the paper and adapted as 75 hereinafter fully described to impart to the fold the push necessary to carry it into engagement with the folding rolls 3 and 4 which completes the loop fold in the usual manner. The curved nose 2 of the upper 80 folding plate 1 is preferably of uniform thickness and is formed by curving the plate substantially uniformly and its extreme edge 5 is arranged in close proximity to the upper squeeze roll and it is adapted 85 to clear the upper squeeze roll 6 which cooperates with the folding roll 3 in feeding the sheet of paper from the feed table 7 of the paper folding machine to the upper and lower folding plates 1 and 8. The 90 lower folding plate 8 which is adjustably secured to the upper folding plate 2 by screws 9 or other suitable fastening devices is provided at the said screws 9 with slots 10 to permit an adjustment of the said 95 lower folding plate so that its lower end 11 may always extend the required distance below the paper level to prevent a sheet of paper from stumbling and not properly entering the space between the upper and lower folding plates 1 and 8. The upper and lower folding plates 1 and 8 are spaced apart in the usual manner and the upward travel of the sheet is limited by an adjustable stop 12 in the usual manner.

The upper folding plate has mounted on it at each side of its lower end a bracket 13 composed of an inner attaching portion 14, an intermediate transversely disposed portion 15 and an outer bearing portion 16 110 which is provided with a longitudinal bearing slot 17 receiving a horizontal stud 18

projecting laterally from the side frame 19 of the folding machine. The bearing bracket 13 is angular as clearly shown in Fig. 2 of the drawings and the longitudinal bearing slot 17 is arranged at an acute angle to the upper folding plate and it is adapted to permit a backward and forward adjustment of the folding plate simultaneously with the angular adjustment of the same to maintain the curved nose in proper position with relation to the upper squeezer roll 6 and the paper level which is in the plane of the upper face of the feed table. The stud 18 is preferably provided with a threaded shank or stem and is mounted in a suitable opening in the side frame 19 of the machine but it may be mounted thereon in any other desired manner. The attaching portion 14 of the bearing bracket is secured by screws 20 to the upper face of the top folding plate and the intermediate transverse portion 15 extends laterally from the side of the folding plate to offset the outer bearing portion therefrom and to arrange the latter in proper position at the outer face of the side frame of the machine to receive the journal stud 18. The top plate is provided with longitudinal slots 21 to receive the projections of the adjustable stop 12.

20 The folding plates are adjustably supported at various angles or inclinations by means of a side supporting bracket 22 consisting of a horizontal attaching portion or base 23 and a curved upwardly extending body portion or post which is provided with a curved series of perforations 24 arranged eccentric or out of a true arc indicated by the line 26 having the stud 18 for its center. The distance of the perforations of the curved series gradually increases as the angle decreases and the said perforations are adapted to receive a horizontal pin 27 which extends into a socket 28 formed in an enlargement 29 of the folding plate. The removable horizontal pin 27 is preferably provided at its outer end with a knurled or otherwise roughened head 30 and it is secured in its adjustment by means of a clamping screw 31 mounted on the enlargement 29 of the upper folding plate 1. The supporting bracket is secured by bolts or screws 32 to the side frame of the folding machine and the body portion of the bearing bracket is preferably curved as shown and it is arranged at an inclination and extends upwardly and forwardly.

It has been found by extensive experiment that the curved nose of the upper folding plate will fold paper practically at any angle and that in fact, the folding improves as the angle is decreased. It has also been found that in reducing the angle, it is possible to lessen the distance between the nose and the paper level until the nose is brought on the same level that the sheet enters and

the lighter stock will go up the incline perfectly. When working the incline at forty-five degrees it is necessary to leave an opening or space from approximately three-sixteenths of an inch between the paper level 70 and the nose. Stiff stock can be driven up an incline perfectly at forty-five degrees while soft light stock which loops easily should be folded in nearer a straight line. It will thus be seen that the space between 75 the curved nose 2 and the paper line or level must vary according to the angle of the folding plates and experience demonstrates that when the plates are set at forty-five degrees the space must be three-sixteenths 80 of an inch; that forty degrees of space is one-eighth of an inch and at thirty-three degrees the nose should be right at the paper line. The increased space at forty degrees and forty-five degrees is provided for the 85 purpose of eliminating friction in making the turn, otherwise the sheet will not travel entirely by the incline. In decreasing the angle of the plates by lowering the same to different openings 25 of the curved eccentric series, the folding plates pivot on the journal stud 18 to a point wherein the curved nose 2 has reached the paper line which is approximately thirty-three degrees. Further decreasing the angle of the nose 95 would cause the nose to pass below the paper line if the folding plate moved in a true arc but this is compensated for by the angular slot 17 and the eccentric series of openings 25. First the folding plates are lowered 100 beyond the angle of thirty-three degrees and to a lesser angle the plates are moved in a backward direction as indicated by the arrow 33 and the angular slot operates to raise the curved nose 2 simultaneous with such rearward movement and maintains the curved nose at the paper line or level and with the extreme edge of the nose in close proximity to but clearing the squeezer roll 6. The openings 25 in the supporting 105 bracket are arranged with a gradual increase from a true arc described from the fulcrum stud as indicated by the line 26 and this increased distance from the pivot or fulcrum stud 18 causes the incline angularly related bearing slot to function and maintain the nose at the paper line or level as the removable pin 27 is adjusted from hole to hole. The convex lower face of the curved nose should be at the paper line at 110 all angles less than thirty-three degrees and the extreme edge or corner 5 of the nose must always just clear the squeezer roll 6 without leaving an opening for the paper to crowd through.

The folding roll 3 and the upper squeezer roll 6 are journaled in suitable bearings carried by the side frame and the folding roll 4 is yieldingly mounted in a slidable bearing 34 and is yieldably maintained in posi-

tion by a coiled spring 35 mounted on a suitable adjusting screw 36 which may be of any desired construction.

In Fig. 3 of the drawing is illustrated another form of the invention in which the upper and lower adjustable folding plates 37 and 38 are supported at each side by a removable block 39 arranged upon the side frame 40 and secured to the same by a screw 41 which engages a threaded socket 42 in the lower face of the removable supporting block 39. The supporting block 39 which is constructed of suitable metal is provided with a horizontal face and an inclined upper face 43 which is adapted to receive the folding plates which are securely anchored to and rigidly held on the supporting block by means of a thumb screw 44 extending through the folding plates and engaging a threaded socket 45 in the upper inclined face of the said block 39. The folding plate 37 is provided with a curved nose and is constructed similar to that heretofore described and the lower folding plate 38 is adjustable similar to that before described by means of screws 46 mounted on the upper folding plate and operating in slots 47 in the lower folding plate. In practice a set of folding blocks will be provided having their inclined faces arranged at different angles and at different elevations to enable the folding plates to be adjusted from the full line position illustrated in Fig. 3 of the drawing to an elevated position at a different angle as illustrated in dotted lines in the said figure. These blocks provide a firm, rigid seat for the folding plates and a perfectly solid structure results in any adjustment of the folding plates. Any number of the removable blocks may be employed and they may be made to correspond with the various adjustments of the folding plates illustrated in Fig. 1 of the drawings. The upper squeezer roll 48 and the lower folding rolls 49 and 50 are arranged with relation to the folding plates as heretofore described and the folding roll 59 is mounted in a slidable bearing 60 and is adjusted by means of a screw 61 connected at its inner end with the slidable bearing 60 and having disposed on it a coiled spring 62 which yieldably maintains the roll 59 in its adjusted position. The screw is equipped at its outer end with a knurled nut 63 and a thumb nut 64 for adjusting and locking the screw 61. In Figs. 4 to 9 inclusive of the accompanying drawings is diagrammatically illustrated the operation of the curved nose in the folding of a sheet. In Fig. 4 of the drawings the sheet 65 is shown as it passes between the plates prior to the buckling action. Fig. 5 shows a sheet starting the natural buckle. This buckle is natural due to the fact that the paper has passed up the incline and come in contact with the stop 12. The upper squeezer roll and the coacting feed roll are still driving the sheet and the natural result or sequence is that the opening between the adjustable curved faces of the folding rolls 3 and 4 will be filled first as shown in Fig. 6. This recess or space between the lower folding rolls having been filled the portion 66 of the sheet 65 will now advance in almost horizontal direction until it comes in contact with the curved nose 2. Fig. 7 shows the portion 66 having come in contact with the curved nose 2 and the paper will now practically fill the space between the upper squeezer roll and the curved nose. The tail of the sheet is continually moving forward which forms a loop in the space between the upper squeezer roll and the curved nose very similar in form to the curved nose. The curved surfaces of the loop and curved nose working against one another forces the fold 67 into the grip of the folding rolls 3 and 4 and the fold is completed as illustrated in Fig. 9 of the drawing. The lower folding plate 8 is a dead surface and the feeding action of the rolls 3 and 6 drive the tail of the sheet and after the space between the lower folding rolls and the curved nose is filled it requires just a slight push to enable the lower folding rolls to grip the sheet. This push is effected by the curved nose through its cam action, otherwise the loop or fold of the paper would cross the opening or space between the curved nose and the lower folding rolls and would cause a series of accordion folds to form in the opening.

All sheets do not form this double or accordion loop. Possibly seventy per cent (70%) of the paper run on any one run may start itself by the natural loop forming as illustrated in Fig. 5 of the drawings and may have a sufficient body to maintain the loop and enter the folding rolls 3 and 4 as indicated by the dotted line in Fig. 5. It has been found by experience that in handling paper it is possible for a machine not equipped with the curved nose to fold with this primary loop for a considerable period of time say six or seven hours, than all at once, due to the condition of the paper it may spoil five sheets out of every ten if the machine is not equipped with the curved nose. Bond paper will invariably fold on the primary loop but cheap bodied stock of a flimsy character may be successfully handled with the curved nose which will handle any stock regardless of the body.

What is claimed is:

1. In loop folding mechanism for paper folding machines, the combination with feeding and folding rolls, of folding plates associated with the said rolls, the upper folding plate having a nose associated with the said rolls and means for adjusting the folding

plates to different inclines or angles between approximately 10 degrees and 45 degrees with relation to the line of feed of the paper and for simultaneously adjusting the said nose to arrange the same nearer the line of feed of the paper as the angle of the folding plates decreases.

2. In loop folding mechanism for paper folding machines, the combination with feeding and folding rolls, of upper and lower folding plates, the upper folding plate being provided at its lower end with a curved nose associated with the said rolls, and means for pivotally adjusting the folding plates on an axis adjacent the curved nose to different angles or inclinations between approximately 10 degrees and 45 degrees with relation to the line of feed of the sheet.

3. In loop folding mechanism for paper folding machines, the combination with feeding and folding rolls, of upper and lower folding plates, the upper folding plate being provided at its lower end with a curved nose associated with the said rolls, and means for adjusting the folding plates to different angles or inclinations with relation to the line of feed of the sheet and for simultaneously effecting a back and forward adjustment of the folding plates.

4. In loop folding mechanism for paper folding machines, the combination with feeding and folding rolls, of upper and lower folding plates, the upper folding plate being provided at its lower end with a curved nose associated with the said rolls, and means for adjusting the folding plates to different angles or inclinations with relation to the line of feed of the sheet and for simultaneously adjusting the nose to vary the distance between the same and the line of fold of the sheet.

5. In loop folding mechanism for paper folding machines, the combination with feeding and folding rolls, of upper and lower folding plates, the upper folding plate being provided at its lower end with a curved nose associated with the said rolls, and means for adjusting the folding plates to different angles or inclinations with relation to the line of feed of the sheet and for simultaneously adjusting the nose to vary the distance between the same and the line of fold of the sheet without changing the distance between the extreme point of the nose and the adjacent roll.

6. In loop folding mechanism for paper folding machines, the combination with feeding and folding rolls, of upper and lower folding plates, the upper folding plate being provided at its lower end with a curved nose associated with the said rolls, and means for adjusting the folding plates about an axis adjacent the curved nose to arrange them at different angles or inclinations between approximately 10 degrees and 45 de-

grees with relation to the line of feed of the sheet and means for effecting an independent adjustment of the lower folding plate to maintain its lower end a predetermined distance below the line of feed of the sheet.

7. In loop folding mechanism for paper folding machines, the combination with feeding and folding rolls, of upper and lower folding plates, the upper folding plate being provided at its lower end with a curved nose associated with the said rolls, means for adjusting the folding plates to arrange them at different angles or inclinations with relation to the line of feed of a sheet and for simultaneously effecting a backward and forward adjustment of the folding plates to vary the distance between the curved nose and the line of feed of the sheet, and means for effecting an independent adjustment of the lower folding plate to cause its lower end to project at all times at a predetermined distance below the line of feed of the sheet to prevent the paper from stumbling.

8. In loop folding mechanism for paper folding machines, the combination with feeding and folding rolls, of folding plates associated with the said rolls, means for slidably and pivotally mounting the folding plates adjacent the said rolls for adjusting the folding plates to different angles or inclinations and for moving the folding plates backwardly and forwardly, and means for supporting the folding plates in their adjustment.

9. In loop folding mechanism for paper folding machines, the combination with feeding and folding rolls, of folding plates associated with the said rolls, means for slidably and pivotally mounting the folding plates adjacent the said rolls for effecting an eccentric adjustment of the folding plates with relation to the axis of one of the rolls to arrange the same at different angles or inclinations and for simultaneously moving the same backwardly or forwardly.

10. In loop folding mechanism for paper folding machines, the combination with feeding and folding rolls, of folding plates associated with the said rolls, means for slidably and pivotally mounting the folding plates adjacent the said rolls for adjusting the folding plates to different angles or inclinations, and means for securing the folding plates in their adjustment including a supporting bracket provided with a curved series of openings arranged eccentric to the axis of the folding plate and fastening means adapted to be arranged in the said openings for securing the folding plates.

11. In loop folding mechanism for paper folding machines, the combination with feeding and folding rolls, of folding plates associated with the said rolls, means for mounting the plates adjacent the said rolls including a fixed pivot and a bearing bracket

- secured to the folding plates and slidably fulcrumed on the said pivot to raise and lower the plates and to move them backward and forward and means for securing the folding plates in their adjustment on the pivot to arrange them at different angles or inclinations at different distances from the line of feed of the paper.
12. In loop folding mechanism for paper folding machines, the combination with feeding and folding rolls, of folding plates associated with the said rolls, means for mounting the plates adjacent the said rolls including a fixed pivot, a bearing bracket secured to the folding plates and having an angularly related bearing slot receiving the said pivot whereby the bracket is slidably and pivotally mounted thereon and means for securing the folding plates in their adjustment on the said pivot.
13. In loop folding mechanism for paper folding machines, the combination with feeding and folding rolls, of folding plates associated with the said rolls, means for mounting the plates adjacent the said rolls including a fixed pivot, a bearing bracket secured to the folding plates and having an angularly related bearing slot receiving the said pivot whereby the bracket is slidably and pivotally mounted thereon, a fixed supporting bracket provided with a curved series of openings arranged concentric with the said pivot, and fastening means adapted to be arranged in the said openings for securing the folding plates to the bracket at different angles or inclinations.
14. In loop folding mechanism for paper folding machines, the combination with feeding and folding rolls, of folding plates associated with the said rolls, means for mounting the plates adjacent the said rolls including a fixed pivot, a bearing bracket secured to the folding plate and having an angularly related bearing slot receiving the said pivot whereby the bracket is slidably and pivotally mounted thereon, a fixed supporting bracket provided with a curved series of openings arranged concentric with the said pivot, a pin adapted to be arranged in the said openings and engaged with the folding plates for securing the same at different angles or inclinations and fastening means for securing the pin in its engagement with the folding plates.
15. In loop folding mechanism for paper folding machines, the combination with feeding and folding rolls, of folding plates associated with the said rolls, and provided with a nose adapted to make a fold at an angle less than 45 degrees and means for supporting the folding plates at an angle substantially less than forty-five degrees and with the nose of the folding plate nearer the line of feed of the paper as the angle of the folding plates decreases.
16. In loop folding mechanism for paper folding machines, the combination with feeding and folding rolls, of folding plates associated with the said rolls, a nose carried by the folding plates for making a fold at an angle less than forty five degrees, and means for supporting the folding plates at an angle substantially less than forty-five degrees and for simultaneously adjusting the nose to arrange the same nearer the line of feed of the paper as the angle of the folding plates decreases.
17. In loop folding mechanism for paper folding machines, the combination with feeding and folding rolls, of folding plates associated with the said rolls, and provided with a curved nose adapted to make a fold at an angle less than forty five degrees and means for supporting the folding plates at an angle substantially less than forty five degrees and with the curved nose less than three-sixteenths of an inch from the line of feed of the paper.
18. In loop folding mechanism for paper folding machines, the combination with feeding and folding rolls, of folding plates associated with the said rolls and provided with a curved nose and supported at an angle substantially less than forty-five degrees and with the curved nose less than three-sixteenths of an inch from the line of feed of the paper.
- In testimony whereof I affix my signature.
- LESTER KYLE ALDRICH.
